UNITED STATES PATENT OFFICE

ALFRED AHLBERG, OF INDIANAPOLIS, INDIANA

HEATING STOVE OR FURNACE

Application filed August 20, 1929. Serial No. 387,187.

The object of this invention is to supply air through grate bars to coal as a fuel in quantities and directions ample to support proper combustion to secure maximum heat.

5 Another object is to provide circulation of air below and through the grate bars to prevent overheating and burning out of the grate.

A further object is to provide means for 10 changing and controlling the location of the fire bed to suit varying conditions of fuel and also of the weather.

The object also is to provide an efficient 15 and convenient means for removing clinker and ashes from the grate bars and for keeping the grate clean.

Still another object of my invention is to provide means for taking cold air from the floor level of the room where the temperature of the room is lowest and heat it in the stove and discharge it to the room at the top of the stove.

A further object is so to circulate the smoke and waste gases of combustion as to 25 remove and retain the heat instead of wasting it by discharging up the chimney.

I accomplish other objects which will hereinafter appear by the device illustrated in the accompanying drawings, in which—

30 Fig. 1 is a side elevation and partial vertical section of a stove embodying my invention;

Fig. 2 is a horizontal section on the line 2—2 of Fig. 1 looking down;

35 Fig. 3 is a front elevation of the stove shown in Fig. 1, with the casing broken away to show the interior construction of the stove; and

Fig. 4 is a view in cross section on the 40 line 4—4 of Fig. 1.

Like characters of reference indicate like parts throughout the several views of the drawings.

45 The stove bottom 4 is supported on the legs 3, at a suitable distance above the floor of the room for the sliding suspension of an ash box 2 from said stove bottom on slides 1, whereby the box may be removed 50 for emptying. A hole 5 is formed in the

bottom for the discharge of ashes into the box.

Supported upon the bottom 4 is a metal housing, here shown as square in cross section and comprising a front 6, a back 7, 55 and two sides 8, 8. Extending up from the bottom 4 to the top of the fire box, here shown as approximately half of the height of the housing, and from front 6 to back 7 are two parallel partitions 9, which confine the fire box 10 within narrower limits than the full width of the stove in order to protect a series of air flues 11, here shown as six in number, extending through the bottom 4 and vertically therefrom to and 60 through a top 12. The partitions are preferably made out of fire clay.

The top 12 closes the housing above referred to. The stove front 6 has an ash-clean-out door 13 near the bottom 4, and in 70 the door is an air opening which is regulated in area by a rotary damper 14. Supported in part by the front 6, just above the door 13, and extending between and into contact with both partitions 9, is a plate 15 75 which is flat for approximately a third of the depth of the fire box and from thence curves upwardly and rearwardly forming the curved member 16 which is supported at the rear by the stove back 7. The curved 80 member 16 is formed with longitudinal slots which define grate bars 17, each having an underside reinforcing flange 18. The grate bars may be cast as an integral part of the member 16, or they may be 85 formed separately for convenience in the renewal of the separate bars, not shown, in case less than the whole member has to be renewed.

Coal is supplied to the fire box, upon the 90 grate bars, from a magazine tube 19, which stands obliquely to the back 7 at an angle of approximately 25 degrees therewith for greatest efficiency with its lower end passing through the back and discharging upon the grate bars. The magazine is preferably 95 oval in cross section to secure the greatest freedom of coal discharge through it and the upper end of the magazine is closed by a lid 20. The coal discharges by gravity 100

from the magazine and down the curved member 16 and its grate bars, but the coal is arrested in its travel toward the front 6 by a baffle plate 21, supported by a base 22, which is slidably adjustable on the flat portion 15. The position of the baffle plate is controlled by a push and pull bar 23 which is attached to the plate 21 and extends through the front 6 to the outside of the stove.

The portion 15 has a clean-out hole 24 which is uncovered by sliding the baffle plate and base forward. The front 6 is preferably formed with a door 25.

Passing freely through a suitable opening in the back 7, below the grate bars, is a bar 26, which is pivotally attached to a hanger 27 having an arm extension slidingly supported by the back 7, whereby the bar 26 is capable of a swinging adjustment on the pivot and also of adjustment longitudinally.

Fixed rigidly on the inner end of the bar 26 is a fork-like member 29 having a tine or blade for each space between the grate bars and adapted to be entered between the grate bars by the longitudinal movement of bar 26, and agitated there, by the additional swinging movement of the bar 26 on its pivot, thereby to break up clinkers at the bottom of the fire bed and work them and ashes down into the ash box by gravity.

A smoke pipe 30, here shown as located centrally above the fire box has its inner end inserted half way to the bottom of a tubular member 31 of much greater diameter, having a closed bottom, thereby compelling the waste gases, etc., to circulate down through the member 31 before entering the outlet 30.

This is to create a circulation within the stove and around the air flues 11 to more thoroughly heat the current of air passing up through said flues.

Coal placed in the magazine feeds down automatically by gravity as the fire consumes the fuel below, upon the curved grate bars until arrested by contact with the baffle plate. The volume of coal under combustion is regulated by so moving the baffle plate that the amount of heat obtained can be regulated to the condition of the weather.

The heat passes up into contact with the air flues heating the current of air passing through the flues, and the indirect outlet to the smoke pipe aids in subjecting the air flues to the maximum heat.

Ashes are thoroughly removed from the grate bars by the manual agitation of the fork fingers and are deposited by gravity in the ash box below the stove bottom leaving the space between the bottom and grate clear in order to avoid burning out the grate bars.

While I have shown the best embodiment of my invention now known to me, it is capable of changes and additions in commercial production without departing from the spirit of the invention and I therefore do not wish to be limited more than is required by the appended claims.

I claim:

1. In a stove or furnace, a housing, a fire box bottom therein comprising a flat portion and a grate bar portion curved upwardly from the flat portion, a fuel magazine discharging by gravity at the top of the curved portion, and a baffle plate on the flat portion to arrest the fuel, said plate being separate from and adjustable toward and from the curved portion.

2. In a stove or furnace, a housing, a fire box bottom therein comprising a flat portion and a grate bar portion curved upwardly from the flat portion, a fuel magazine discharging by gravity at the top of the curved portion, and a baffle plate on the flat portion to arrest the fuel, said plate being separate from and adjustable toward and from the curved portion, said curved grate bar having a cleaner located below the curved portion and movable between and past the grate bars and manually operated means for actuating the cleaner.

3. In a stove, a housing, a pair of partitions dividing the lower end of the housing into three compartments, grate bars located in the middle compartment a baffle plate movable in the middle compartment relative to the grate bars to vary the area and location of the fire area in said compartment, and air flues located in the two outer compartments extending through the housing and out through the bottom and top of the housing the baffle plate being located in front of the grate bars.

4. In a stove, a housing, a pair of partitions dividing the lower end of the housing into three compartments, grate bars located in the middle compartment, air flues located in the two outer compartments extending through the housing and out through the bottom and top of the housing, and means located in front of the grate bars to vary the position and extent of the fire in the fire pot.

5. In a stove, a housing having a bottom and a top, a pair of partitions dividing the lower end of the housing into three compartments, grate bars located in the middle compartment a baffle plate movable in the middle compartment relative to the grate bars to vary the area and location of the fire area in said compartment, air flues located in the two outer compartments extending through the housing and out through the bottom and top of the housing, a smoke pipe, and means by the passage of waste products of combustion to the smoke pipe

for circulating the air around the outside of the air flues the baffle plate being separate from and located in front of the grate bars.

5 6. In a stove or furnace, a housing having a fire box, a grate in the fire box, a fuel magazine oblique to the housing and discharging by gravity through its lower end into the fire box upon the grate and a baffle plate
10 at the opposite end of the grate bar from the fuel magazine having reciprocating adjustment toward and from the magazine to change the fire area.

7. In a stove or furnace, a housing having
15 a fire box, a grate in the fire box, a fuel magazine oval in cross section oblique to the vertical and discharging by gravity through the walls of the housing upon the grate and a baffle plate at the opposite end of the
20 grate bar from the fuel magazine having reciprocating adjustment toward and from the magazine to change the fire area.

8. In a stove, a housing, a pair of partitions dividing the lower end of the housing
25 into three compartments, air flues located in the two outer compartments extending through the housing and out through the bottom and top thereof, a firebox bottom in the middle compartment comprising a
30 front flat portion and a grate bar portion curved upwardly and rearwardly from the flat portion, a fuel magazine discharging by gravity onto the top of the grate bars, and a baffle plate in the flat portion to arrest the fuel said plate being adjustable toward and from the curved portion to vary the fire area.

9. In a stove, a housing, a pair of partitions dividing the lower end of the housing
40 into three compartments, air flues located in the two outer compartments extending through the housing and out through the bottom and top thereof, a firebox bottom in the middle compartment comprising a front
45 flat portion having a clean out hole therethrough and a grate bar portion curved upwardly and rearwardly from the flat portions, a fuel magazine discharging by gravity onto the top of the grate bars, a baffle
50 plate on the flat portion to arrest the fuel and normally cover and close the clean out hole, said plate being movable toward and from the grate bars to regulate the clean out and to vary the fire area, a tubular mem-
55 ber above the middle compartment having a closed bottom, and a smoke pipe having its intake end located in the tubular member.

In testimony whereof I affix my signature.

60 ALFRED AHLBERG.
